(57) **CLAIM**

The ornamental design for a lighting fixture, as shown and described.

DESCRIPTION

FIG. 1 is a front view of a lighting fixture showing our new design, the rear view, the left side view and the right side view being identical to the front view.

FIG. 2 is a top view thereof.

FIG. 3 is a bottom view thereof.

FIG. 4 is an enlarged cross-sectional view taken along line 4—4 in FIG. 2 with the internal parts omitted; and,

FIG. 5 is an enlarged view of an indicated portion in FIG. 4. The portions shown in double cross-hatched lines in FIGS. 4 and 5 are transparent.

1 Claim, 4 Drawing Sheets
